UNITED STATES PATENT OFFICE.

WILLIAM MURRAY, OF BROOKLYN, NEW YORK, ASSIGNOR OF ONE-HALF TO JAMES H. MURPHY, OF BAYONNE, NEW JERSEY.

SAFETY-SIGNAL FOR POWER-VEHICLES.

1,241,421.

Specification of Letters Patent. Patented Sept. 25, 1917.

Application filed June 8, 1916. Serial No. 102,386.

To all whom it may concern:

Be it known that I, WILLIAM MURRAY, a citizen of the United States, and resident of the borough of Brooklyn, county of Kings, city and State of New York, have invented certain new and useful Improvements in Safety-Signals for Power-Vehicles, of which the following is a specification.

My invention relates to devices to be used on power vehicles, such as automobiles or street-cars, for the purpose of giving a warning to the operators of other automobiles or cars, of operations, such as the applying of the brakes, which are frequently the cause of collisions and like accidents. With my improved safety signal, the chauffeur of a car following behind one equipped with my improvement, would become aware of the fact that the car ahead was going to be slowed down or stopped by the application of the brakes, even before he could observe the effect of the brakes, and thus he would be given more time in which to avoid a collision. The invention will now be described in detail with reference to the accompanying drawings, and the features of novelty will then be pointed out in the appended claims.

Figure 1 is a front elevation of one form of my improved safety signal, with parts in section; Fig. 2 is a side elevation thereof, with the casing in section on line 2—2 of Fig. 1; Fig. 3 is a detail vertical section of a stop forming part of my signal; Fig. 4 is a rear elevation of the device; Figs. 5 and 5^a are detail vertical sections illustrating one way of operating my improved signal by the usual foot-brake of an automobile; Fig. 6 is a diagram illustrating the electric circuits; and Figs. 7 and 8 are detail views, in elevation and horizontal plan respectively, outlining a way of operating my improved signal by means of the brake-controller lever of a trolley car.

The mechanism of my improved signal is shown located in a box or casing A of rectangular shape, and this casing is provided at the rear with an opening or sight A' (which may be covered by a transparent pane A'', if desired) through which, at certain times, the sign or signal proper B will become visible. This sign consists of a plate bearing a suitable word, say the word Brake as in Fig. 4, in white letters on a dark background, or in any other readily visible way.

Normally, the sign is concealed from view by a screen or shutter C, see Fig. 2. This screen, of substantially rectangular shape, is secured to two arms C' carried by a rock shaft D journaled in the casing A. The plane of the screen is preferably perpendicular to radial lines drawn from the axis of the shaft D to the central portion of the said screen. The arms C' are weighted on the side of the fulcrum opposite to the screen C, so as to partly counterbalance said screen. The weight of the screen should however be sufficient to cause it to drop normally to the active or concealing position shown by full lines in Fig. 2, a stop E secured within the casing serving to limit the downward movement of the said screen and to determine its normal position. On the rock-shaft D is also secured rigidly an armature F adapted to be attracted by the poles of an electromagnet G. The electromagnet G is connected by wires G', G'' with binding posts H, H' respectively. To operate the signal, by causing the screen C to swing up and expose the sign B to view, I may, as shown in Figs. 5, 5^a, and 6, connect the binding post H by a wire J with a contact spring K located in the path of a portion of the foot-brake lever L (fulcrumed at L'), but normally out of contact therewith. This lever is adapted to engage at the same time with the spring K, a similar spring K' connected by a wire J' with a source of electricity, such as a battery M. The other pole of said battery is connected by a wire J'' with the binding post H'. With this arrangement, as soon as the lever L is swung forward to apply the brake, the circuit including the electromagnet G will be closed as follows: battery M, wire J', contact spring K', lever L, contact spring K, wire J, binding post H, wire G', coils of electromagnet G, wire G'', binding post H', and back to the battery M through wire J''. The magnet being energized will attract the armature F and lift the screen C to the position shown by dotted lines in Fig. 2. The brake sign B will thus be clearly exposed to view, and since the device is so located on the automobile as to be readily visible to the chauffeur of another motor car following in the rear, quick warning will be given of the fact that the brakes are being applied, even before the braking action itself becomes noticeable to the driver of the car following.

in the rear. Accidents through collision or the like are therefore prevented, or at least the danger of such accidents is reduced considerably. A convenient position for the 5 apparatus would be on one of the rear mudguards.

Inasmuch as a power vehicle is often subjected to jars, it is desirable to lock the screen C in its normal or active position, to 10 prevent it from being thrown up accidentally into the active position in which the brake sign is visible. For this purpose, one of the arms C' is normally engaged, on the side of the shaft D opposite to that on which 15 the stop E is arranged, by a bolt N adapted to slide under said arm, and, in conjunction with said stop, the sliding bolt will normally lock the arm C' and the screen connected therewith. The bolt N slides in a suitable 20 stationary guide O, in a direction parallel to the shaft D, and is made of iron or other suitable material, so that it may be attracted by the electromagnet G, adjacent to which it is located on the same side of both electromagnet cores, so that each core will 25 attract the armature or bolt in the same direction. A spring N' tends to restore the locking bolt N to its normal position, in the path of the arm C', while the magnet G, when 30 energized, will withdraw the bolt N from the path of said arm, the magnetic attraction acting in opposition to the spring N'. So when the magnet circuit is closed in the manner described above, the first effect will be 35 to retract the bolt N from its locking position, and then the armature F with the screen C will be swung as described above to uncover the brake sign B. When the circuit is broken upon the return of the brake 40 lever L to its normal position, the weight of the screen C will cause it to drop back to its normal position; upon the breaking of the circuit, the bolt N has been shot back to its normal position by the spring N', and 45 lies above the arm C', and in the path thereof. As this portion of the arm C' swings up during the return of the screen C to its normal position, it comes in contact with the bolt, and in order to allow the latter 50 to yield so that the arm C' may pass by, those portions of the arm and of the bolt which meet during the return swing of the arm are properly shaped, as by beveling the upper surface of said arm at C'' and the 55 under surface of the bolt. When this portion of the arm has swung up past the bolt N, the spring N' will restore the bolt to the normal locking position.

At night the signal might be lighted by a 60 suitable lamp P located in the rear of the casing A above the opening A' and under a hood Q which may act both as a protector for the lamp and as a reflector to throw its light on the sign B. The lamp P may be in

the ordinary lighting circuit of the automobile, to burn permanently as long as the other lights are burning. It is preferable, however, for the sake of economy, to light the lamp P only at such times as the screen C is lifted to uncover the sign B. For this 65 purpose, the swinging screen C may be connected with a circuit-closer for said lamp P, for instance as follows: One of the arms C' is adapted to fit between two stationary, yielding contact members or springs R, R' at 70 the time the screen is fully lifted (see dotted lines in Fig. 2). One of these contact springs is connected by a wire S with the binding post H, the other contact spring is connected by a wire S' with one terminal 75 of the lamp P, and the other terminal of said lamp is connected by a wire S'' with the binding post H'. A switch T (Figs. 1 and 6) may be included in the lamp circuit, and in daytime this switch could be turned off, 80 as shown in Fig. 6, since the lamp would not be required. This switch T would of course be located so as to be readily accessible. It will be seen that the lamp circuit 85 forms a shunt to the circuit of the electromagnet G, both being supplied with current from the battery M or other source of electricity. It will also be observed that at 90 first only the electromagnet circuit is closed, the full strength of the battery current passing into said electromagnet circuit, and this is an advantage inasmuch as it insures a proper operation of the screen C even when the battery M is almost run down. The current enters the lamp circuit only when the 95 screen C has already reached the position in which it uncovers the sign B. The circuit-closer or switch formed by the lever L in conjunction with the contact springs K, 100 K' is in the circuit of the lamp P as well 105 as in the circuit energizing the electromagnet G. Thus, should the armature F for any reason stick in the attracted position, the lamp circuit would nevertheless be broken by the return of the lever L to its normal 110 position, Figs. 5* and 6. That is to say, the switch K, K', L is in the circuit portion (H', J'', M, J', J, H) which may be said 115 to be common to the electromagnet circuit and to the lamp circuit, and is arranged at a point between the source of electricity M and one of the points of junction of the separate portion (G', G, G'') of the electromagnet circuit with the separate portion (S, S', P, S'') of the lamp circuit.

In Figs. 7 and 8, I have shown a brake-controller lever U of the kind commonly used on trolley cars, and said lever might be made with a projection U' which, in the position of the controller which applies the brakes, would complete the circuit of the electromagnet G by engaging two stationary spaced contact members or springs V, 125

V' connected to the wires J, J'; that is to say, these springs V, V' would correspond to the springs K, K', and the lever U to the lever L, the operation being perfectly analogous to the one described above.

Of course, I do not restrict myself to the details of construction shown, nor to operating my signal by the foot-brake lever of a motor-car, or by the brake-controller-lever 10 of a trolley-car, but I wish it to be understood that various modifications may be made without departing from the nature of my invention as defined in the appended claims.

15 I claim as my invention:

1. A signal, particularly for power vehicles, provided with a member movable from an active position to an inactive position, a pivoted arm extending from said member to and beyond the axis about which such member swings with said arm, a device for engaging and locking said arm on the side of said axis opposite to said member when the latter is in one of its positions, and means for moving said device to a releasing position and causing said member to assume its other position.

2. A signal, particularly for power vehicles, provided with a swinging member movable from an active position to an inactive position, a slide movable in a direction parallel to the axis about which said member swings, and adapted to lock said

member, and means for effecting movement of said slide and of said swinging member. 35

3. A signal, particularly for power vehicles, provided with a rocking member movable from an active position to an inactive position, an armature connected with said member, an electro-magnet for attracting said armature, a slide adapted to lock said member and movable toward and from said electro-magnet, said slide being of magnetic material, and a spring for moving said slide away from the electro-magnet. 40 45

4. A signal, particularly for power vehicles, provided with a member movable from an active position to an inactive position, a pivoted arm extending from said member to and beyond the axis on which said member swings with said arm, a device for engaging and locking said arm on the side of the said axis opposite to said member, said device being of magnetic material, an armature connected with said member, an electro-magnet located in attracting relation to said armature and to said locking device, a circuit-closer in operative relation to said swinging parts, and a circuit associated with said circuit-closer 50 55 60 and including means for calling attention to the signal when said swinging member reaches its signaling position.

In testimony whereof, I have signed this specification.

WILLIAM MURRAY.
